LE ROY C. SCHENCK, OF EAST MOLINE, ILLINOIS, ASSIGNOR TO TROY LAUNDRY MACHINERY CO., INC., OF EAST MOLINE, ILLINOIS, A CORPORATION OF DELAWARE

SINGLE BELT REVERSING MECHANISM

Application filed August 21, 1929. Serial No. 387,278.

This invention relates to improvements in machines of the type employing continuously rotating or oscillating working means, and has reference more particularly to laundry machines wherein a power driven belt is used to actuate an oscillating, working cylinder.

At the present time the various types of laundry machines in use can be classified as those employing an electric motor mounted on the machine which, through a system of gearing, transmits the power required to actuate the working cylinders, and those types employing power driven belts and a plurality of pulleys which, through suitable gearing, transmit the required rotation to the cylinders. The improvements of the present invention have been designed for machines of the latter class and especially for the type of machine embodying single gearing mechanism for transmitting the power to the cylinders wherein, in combination with single gearing, a tube drive shaft is employed.

In the operation of laundry machines to which this invention applies it is necessary to have a working cylinder which is given an oscillating movement. The power as delivered to the machine from power driven belts is, of course, continuous rotary movement, and to secure the necessary oscillating movement a reversing mechanism is employed which, at the present time, has required additional parts in the way of belts, pulleys and drive shafts, which have all contributed in adding to the size of the unit, and consequently requires excessive floor space for its accommodation.

It is therefore an object of this invention to provide belt driven laundry machines with a mechanism which will transform continuous rotary movement as delivered by the belt to oscillating movement when applied to the cylinders.

Another object of the invention is to provide belt driven laundry machines with that type of reversing mechanism which will eliminate the rear drive shaft now in use, and which will require but a single power driven belt for its operation.

A still further object of the invention is to secure a reversing mechanism that can be ap-

plied to belt driven laundry machines which will require in its construction a minimum number of parts, which will be positive in operation, and which will not project beyond the front or rear of the machine, thereby conserving valuable floor space.

Yet another object of the invention is to provide a reversing mechanism which will eliminate in its construction the use of clutches, friction drives and complicated gearing, all of which have proven impractical for everyday operation.

With these and various other objects in view, the invention may consist of certain novel features of construction and operation, as will be more fully described and particularly pointed out in the specification, drawings and claims appended hereto.

In the drawings, which illustrate an embodiment of the device and wherein like reference characters are used to designate like parts—

Figure 1 is an end view of a belt driven laundry machine embodying the features of the present invention;

Figure 2 is a side elevation of the machine showing the reversing mechanism as applied thereto;

Figure 3 is a top plan view showing a preferred embodiment of the reversing mechanism;

Figure 4 is a side view of the reversing mechanism showing in detail a preferred form of belt shifting device;

Figure 5 is an end view of the reversing mechanism showing a modified form of belt arrangement; and

Figures 6, 7 and 8 are plan views showing the arrangement of the pulleys with the belt in its left hand, intermediate and right hand positions, respectively.

The laundry machine 10 is a conventional type of machine and is equipped with a trunnion gear 12 which has operative engagement with the working cylinder of the machine through a central drive shaft not shown. It is seen, therefore, that whatever rotary or oscillating movement may be imparted to the trunnion gear 12, a like movement will be given to the working cylinder.

The machine 10 has secured to one end thereof or through any suitable securing means a housing member 14. The housing member is provided with a plurality of bearing apertures 16 for the accommodation of a plurality of bearing members 18. Mounted within the housing member and journaled in the bearings 18 are disposed two transverse drive shafts 20 and 22. The drive shaft 20 has securely mounted thereon at its inner end a narrow pulley 26 which is preferably keyed to the shaft by some suitable means. Adjacent the narrow pulley 26 and loosely journaled on the drive shaft 20 is a wide pulley 28. At the extreme inner end of the drive shaft 20 a pinion 30 is securely fastened by keying or other means, which pinion has direct meshing engagement with the trunnion gear 12. The drive shaft 22 is of a similar construction, with the exception that the narrow pulley 32, which is securely mounted on the shaft 22 and preferably keyed thereto by suitable means, is disposed at the extreme right hand end of the shaft which is in staggered relation to the narrow pulley 26 on the shaft 20. Mounted adjacent to the pulley 32 at the inner end of the shaft 22 is a loosely journaled wide pulley 34 similar to the pulley 28. At the extreme inner end of the shaft 22 there is securely mounted, by keying or other suitable means, a pinion 36 which has direct meshing engagement with the trunnion gear 12 in a manner similar to pinion 30. A third shaft 24 which is also journaled in the bearings 18 within the housing 14 is merely an idler shaft and has mounted thereon an idler pulley 38.

In the operation of the mechanism thus far described it will be seen that, with the belt 40 in its extreme right hand position, referring to Figures 3 and 8, the belt will have engagement with the journaled pulley 28 on the drive shaft 20 and with the keyed pulley 32 on the drive shaft 22. With the rotation of the belt as shown by arrows in Figure 1, a counter-clockwise rotation will be imparted to the keyed pulley 32 and consequently to the drive shaft 22. The journaled pulley 28 in this instance merely performs the function of an idler pulley and therefore will not transmit its rotation to the shaft 20. As a consequence, the desired rotation is imparted to the drive shaft 22 and through the pinion 36 to the trunnion gear 12.

Referring to Figure 1, it is seen that the drive shafts 20 and 22 have opposite rotation, as shown by the arrows. To impart a reverse rotation to the trunnion gear 12 it will therefore only be necessary to discontinue the rotary movement imparted to the drive shaft 22 and to bring into operation the rotation of the drive shaft 20. To secure this the belt is shifted to its extreme left hand position, as shown in Figure 6. In this position the

belt has engagement with the keyed pulley 26 on the drive shaft 20 and with the journaled pulley 34 on the drive shaft 22. In this instance the latter pulley will function as an idler pulley and therefore its rotation will not be imparted to the shaft 22. The desired rotation, however, is given to the shaft 20 since the keyed pulley 26 is in operative engagement with the belt. This shaft has a clockwise direction of rotation, and, through the pinion 30 will impart a rotation to the trunnion gear 12 opposite to that imparted when the drive shaft 22 was functioning.

The reversing mechanism is adapted to various forms of belt arrangements wherein Figure 5 discloses a modified form. The same direction of rotation is imparted to the various pulleys as is given in the belt arrangement shown in Figure 1. These various arrangements adapt themselves to various types of ceiling drive shafts.

To accomplish continuous reversals in the rotation as given to the trunnion gear 12 it is seen that it is only necessary to shift the belt from its extreme right hand position of Figure 8 to its extreme left hand position as shown in Figure 6, and vice versa. This is accomplished by a belt shifting device as shown in Figure 4. The journaled pulley 34 mounted on the drive shaft 22 has provided on its hub portion a conventional type of worm gear 42. This worm gear meshes with a suitable chain of gears 44 and 46 and provides rotation for an eccentric pin 48. The eccentric pin 48 has direct engagement with a cam 50 which, upon rotation of the gear 46 and consequent rotation of the pin 48, will be given a sliding movement. This movement is imparted to a belt shifting lever 52 through any suitable form of fastening or connecting means with the cam 50.

In the operation of the reversing mechanism a continuous rotary movement is imparted to the pulley 34 since the belt 40 employed is of a width slightly larger than the width of the narrow pulley 32, which allows for a slight overlapping of the belt 40 on the pulley 34. The rotation of the pulley 34 is transmitted through the gears as described, which causes a consequent shifting back and forth of the belt lever 52. This lever is in direct engagement with the belt 40 and therefore gives a consequent shifting motion to the belt.

As the belt assumes its various positions shown in Figures 6, 7 and 8, the drive shaft 20 will first be actuated through contact of the keyed pulley 26 with the belt, and rotation will be given to the working cylinder of the machine through the trunnion gear 12 and pinion 30 on the shaft 20. As rotation continues the belt 40 is, however, through the shifting device described, shifted to the intermediate position of Figure 7 where both

5 journaled pulleys are in engagement with the belt. In this position neither drive shaft is in operation, and the cylinder will momentarily come to rest. The belt will be shifted further to the right, however, until it assumes its extreme right hand position wherein the keyed pulley 32 will be in engagement with the belt, and, through the shaft 22 and pinion 36, will impart a reverse 10 direction of rotation to the trunnion gear and cylinder.

15 It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

20 26 I claim—

1. In a device of the character described, in combination, a plurality of driving shafts, a pinion mounted on each shaft, a gear adapted for rotation and meshing with each 25 pinion, a plurality of pulleys mounted on each shaft including a pulley securely keyed to the shaft and a pulley loosely journaled thereon, the keyed pulley on each shaft having opposite it the journaled pulley on the other shaft, a belt in engagement with a pulley on each shaft, and means having operative engagement with one of the journaled pulleys for shifting the belt, whereby rotation is given to that shaft having its keyed pulley in engagement with the belt.

30 2. In a device of the character described, in combination, a plurality of driving shafts, a gear adapted for rotation and having engagement with each shaft, a plurality of 35 pulleys mounted on each shaft including a pulley securely keyed to the shaft and a pulley loosely journaled thereon, a belt engaging the keyed pulley of one shaft and the journaled pulley of the other shaft and imparting opposite rotation to the pulleys respectively, and a belt shifting device whereby reversals in the rotary movement imparted to the gear are secured.

35 3. In a device of the character described, in combination, a driving shaft, a pulley mounted on said shaft and keyed thereto, a second pulley loosely journaled on said shaft, a second shaft disposed adjacent the first shaft having a keyed and journaled pulley 40 thereon in staggered relation to the pulleys on the first mentioned shaft, a gear having operative engagement with both shafts, a belt in engagement with the keyed pulley of one shaft and the journaled pulley of the adjacent shaft, and belt shifting means whereby oscillating movement is imparted to the gear.

40 4. In a device of the character described, in combination, a plurality of driving pinions, a shaft mounted for rotation and to 45 which one of the pinions is secured, a second

shaft mounted for rotation and to which the other pinion is secured, a gear mounted for rotation and meshing with both pinions, a keyed pulley and a journaled pulley mounted on each driving shaft in staggered relation, 70 a belt in engagement with a pulley on each shaft, whereby rotation is given to that shaft having its keyed pulley in engagement with the belt.

5. In a device of the character described, 75 in combination, a plurality of driving shafts, a pinion mounted on each shaft, a gear mounted for rotation and meshing with each pinion, a plurality of pulleys mounted on each shaft, including a pulley keyed to the shaft and a pulley journaled on the shaft, the keyed pulley on each shaft having opposite it the journaled pulley on the other shaft, a belt having engagement with a pulley on each shaft, and a belt shifting device, whereby rotation is given to that shaft having its keyed pulley in engagement with the belt.

80 6. In a device of the character described, 90 in combination, a plurality of driving shafts, a plurality of pulleys mounted on each shaft, including a pulley keyed to each shaft and disposed in staggered relation to each other, a belt for engaging the pulleys and imparting rotation thereto, and means for shifting the belt whereby rotation is imparted to 95 either shaft as desired.

7. In a reversing mechanism of the character described, a driven gear, a plurality of driving shafts each provided with a pinion engaging the gear, a plurality of pulleys mounted on each shaft, including a pulley keyed to each shaft and disposed in staggered relation to each other, and means for alternately imparting rotation to the keyed pulleys in opposite directions to impart oscillating movement to the gear.

100 8. In a reversing mechanism of the character described, a driven gear, a plurality of driving shafts each provided with a pinion engaging the gear, a pulley keyed to each shaft, a belt for actuating the pulleys, and means for alternately engaging the belt with the keyed pulley of one shaft to turn it in one direction and then the keyed pulley on the other shaft to turn it in the other direction, whereby oscillating movement is imparted to the gear.

110 9. In a reversing mechanism of the character described, a plurality of driving shafts, a plurality of pulleys mounted on each shaft, including a pulley keyed to the shaft and a pulley journaled thereon, a belt for actuating selectively in opposite directions the keyed pulley on each shaft, and means for shifting the belt comprising a gear operated by the rotation of one of the journaled pulleys, an eccentric secured to said gear and a cam actuated by said eccentric.

115 10. In a reversing mechanism of the character described, a system of driving shafts, a 130

set of pulleys mounted on each shaft, including a pulley keyed to each shaft and disposed in staggered relation to each other, a belt for imparting rotation to the pulleys on the respective shafts in opposite directions, and
6 means for shifting the belt comprising an eccentric and a cam engaging the eccentric.

11. In a reversing mechanism of the character described, a plurality of driving shafts,
10 a plurality of pulleys mounted on each shaft including loose and keyed pulleys on each shaft, a belt for successively engaging and imparting rotation to the pulleys on each shaft, and means for shifting the belt.

15 Signed at East Moline, Ill., this 7th day of August, 1929.
